UNITED STATES PATENT OFFICE.

EMIL E. NOVOTNY, OF RIVERSIDE, ILLINOIS, ASSIGNOR TO J. STOGDELL STOKES, OF MOORESTOWN, NEW JERSEY.

COMPOSITE PLATE.

1,377,508.

Specification of Letters Patent. Patented May 10, 1921.

Application filed December 30, 1916. Serial No. 139,723.

To all whom it may concern:

Be it known that I, EMIL E. NOVOTNY, a citizen of the United States, residing at Riverside, in the county of Cook and State 5 of Illinois, have invented certain new and useful Improvements in Composite Plates, of which the following is a specification.

This invention relates to a composite plate which is especially adapted for making 10 matrices from which printing plates may be molded or cast, and in some instances such sheet may be employed for making the plate itself, if desired.

In carrying out the present invention it is 15 my purpose to provide a composite sheet which may be furnished to the printer in blank form so that he may readily, economically and conveniently prepare his own matrices and plates by an exceedingly simple method, involving heat and pressure applied through the agency of an ordinary 20 press, thus obviating the expense and delay incident to having his printing plates made at an outside establishment making a 25 specialty of such work.

Furthermore, it is my object to provide a composite sheet of this character which will possess the desired characteristics of strength, toughness, durability and which is 30 practically unchangeable when made up in the form of a matrix, or a printing plate, so that when used as a matrix the type produced therefrom will possess sharply defined, clear cut type faces, while when made 35 up in the form of a printing plate the resulting printing will appear uniform and of full tone.

With the above recited objects and others of a similar nature in view my invention 40 consists in the improved composite sheet, set forth in and falling within the scope of the appended claims.

In the accompanying drawings:

Figure 1 is a cross sectional view taken 45 through a preferred form of composite sheet embodying my invention.

Fig. 2 is a view showing the use of a press in the making of a matrix from the composite sheet shown in Fig. 1.

Fig. 3 is a cross sectional view taken 50 through the complete matrix.

Fig. 4 is a cross sectional view taken through a printing plate made with the composite sheet of Fig. 1.

55 Referring now particularly to Figs. 1 to

4 inclusive, in the practice of my invention I first select a layer or sheet of fibrous spongy absorbent material, such as heavy blotting paper, which is indicated by the numeral 1, and this blotting paper I saturate 60 or impregnate with a solution of a synthetic resin such as a phenolic condensation product or phenolic material in its liquid form of which there are several well known 65 grades and varieties, such as liquid bakelite and condensite. The blotting paper readily absorbs this liquid phenolic material which is shown at 2 and when a sufficient amount of the phenolic liquid has been incorporated or 70 absorbed by the paper, a facing sheet or 75 layer preferably of thin copper or copper foil, shown at 3, is imposed upon the saturated paper sheet and the two sheets are then subjected to sufficient heat and pressure to bring the phenolic liquid to its intermediate stage where it is of no longer liquid form, but possesses a certain degree of plasticity 80 and elasticity. In some cases a binder may be necessary to insure the adherence of the facing sheet 3 to the saturated paper sheet, 85 and in such instances any suitable form of binding material or varnish, such as a phenolic varnish, over which may be sprinkled or dusted wood flour or the like may be employed to bind the layers or sheets together. 90

When the composite sheet consisting of the backing layer of the phenolic saturated blotting or absorbing paper, and the facing sheet, is prepared as above described, it is ready for use in making the matrices and 95 plates, and may be furnished to the printer, who may make such matrices or plates directly from his own type forms. This may be done by an exceedingly simple method. For instance, an ordinary form of press is indicated as an entirety by the letter P and comprises in the present instance the bed section 5 and the top platen section 6, and these two press sections are preferably arranged so as to be heated and cooled as may be desired as by fluid inlet pipes, I, and fluid outlet pipes, O. Upon the bed of the press is placed the type body shown at T and which may be ordinary type mounted in the usual chase or may be a printing plate itself. 100 Bearers 7 are arranged upon the bed at the sides of the type body so as to limit the downward movement of the top platen of the press and consequently the depth of penetration of the type faces into the mate- 110

rial. A sheet, such as is shown in Fig. 1, is now placed upon the body of type with the facing sheet 3 in contact with the type faces and the press is closed and heat and pressure applied to produce in the face sheet 3 type formed depressions which are complementary to the type faces of the type body T. Heat is maintained on the press for a sufficient length of time, say for from 10 one to five minutes, to allow the matrix to set to a less plastic state, but not sufficiently to prevent the flexing or bending of the sheet when removed from the press, as it may in some instances be desired to curve 15 the sheet to form a curved matrix, as may be readily done by rolling or bending the sheet about a suitable mandrel when warm. However, if a flat plate is to be made from the matrix, the latter is permitted to harden 20 and cool in the press, and may then be removed therefrom when it will have the appearance shown in Fig. 3. This matrix may then be placed in any ordinary casting box and a plate cast therefrom, the type faces 25 of the plate of course being identical with those of the type body, but will have well rounded, nonprinting portions and sharply defined printing faces. If desired, the composite sheet shown in Fig. 1 may be used 30 for making the printing plate itself, and in this instance the composite sheet is placed with the facing 3 downward against the molding face of the matrix shown in Fig. 3 and heat and pressure applied in the casting 35 box so that the plate when hardened and set will have the appearance shown in Fig. 4, where the plate is indicated by the numeral 8, the printing face thereof being indicated by the numeral 3'. Such a composite plate 40 naturally possesses certain manifest advantages from the standpoints of convenience, ease of manipulation and inexpensiveness in

the production of printing plates and matrices.

What I claim is:

1. A composite sheet comprising an absorbent body having incorporated therein a resinous condensation product capable of assuming a state of plasticity and of assuming a hard and set condition under heat and pressure, and a facing sheet of metal united with said body. 45

2. A composite sheet comprising a fibrous body having incorporated therein a phenolic condensation product capable of assuming 55 a state of plasticity and of assuming a hard and set condition under heat and pressure, and a metallic facing sheet imposed upon said fibrous body.

3. A composite sheet comprising an absorbent body impregnated with a synthetic resin capable of assuming a state of plasticity, and of assuming a hard and set condition under heat and pressure, and a facing 60 sheet of metal united therewith, said facing sheet being provided with depressions and elevations. 65

4. A composite sheet comprising a fiber sheet impregnated with a synthetic resin capable of assuming a state of plasticity and 70 of assuming a hard and set condition under heat and pressure, and a non-fibrous facing sheet imposed upon the impregnated fiber sheet.

5. A composite sheet comprising a fiber 75 sheet impregnated with a synthetic resin capable of assuming a state of plasticity, and of assuming a hard and set condition under heat and pressure, and a non-fibrous facing sheet imposed upon the fiber sheet 80 and having elevations and depressions formed thereon.

In testimony whereof I affix my signature.

EMIL E. NOVOTNY.
